UNITED STATES PATENT OFFICE.

JOHN M. BRENNAN, OF ROXBURY, MASSACHUSETTS.

DESIGN FOR A ROLLING-HOOP.

49,601.

Specification for Design.

Patented Sept. 5, 1916.

Application filed February 5, 1916. Serial No. 76,473. Term of patent 3½ years.

To all whom it may concern:

Be it known that I, JOHN M. BRENNAN, a citizen of the United States, residing at Roxbury, in the county of Suffolk and State of Massachusetts, have invented a new, original, and ornamental Design for Rolling-Hoops, of which the following is a specification, reference being had to the accompanying drawing, forming part thereof.

In the said drawing Figure 1 is an elevation, and Fig. 2 is a circumferential face view of a rolling hoop, showing my new design.

I claim:

The ornamental design for a rolling hoop as shown.

JOHN M. BRENNAN.
